United States Patent

Des. 236,020
Patented July 22, 1975

236,020

STAMPED BEARING ASSEMBLY

Vincent C. Wachter, Milford, Joseph R. Keller, Fairfield,
and Frederick J. Feldmann, Stratford, Conn., assignors
to MPB Corporation, Keene, N.H.

Original design application Aug. 27, 1971, Ser. No.
175,800, now Patent No. 203,030. Divided and this
application July 27, 1973, Ser. No. 383,404

Term of patent 14 years

Int. Cl. D15—99

U.S. Cl. D46—1 R

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a perspective view of one side of the stamped bearing assembly of the present invention;

FIG. 2 is a plan view of the other side of the stamped bearing assembly of FIG. 1;

FIG. 3 is a side view of the stamped bearing assembly of FIG. 1;

FIG. 4 is an end view of the stamped bearing assembly of FIG. 1;

FIG. 5 is a perspective view of an alternative embodiment of the stamped bearing assembly of the present invention;

FIG. 6 is a plan view of the stamped bearing assembly of FIG. 5;

FIG. 7 is a side view of the stamped bearing assembly of FIG. 5;

FIG. 8 is an end view of the stamped bearing assembly of FIG. 5;

FIG. 9 is a perspective view of another embodiment of the stamped bearing assembly of the present invention;

FIG. 10 is a plan view of the stamped bearing assembly of FIG. 9;

FIG. 11 is a side view of the stamped bearing assembly of FIG. 9; and

FIG. 12 is an end view of the stamped bearing assembly of FIG. 9.

This is a division of Ser. No. 175,800, filed Aug. 27, 1971, now Pat. D. 203,030, Feb. 5, 1974.

We claim:

The ornamental design for a stamped bearing assembly, as shown and described.
